UNITED STATES PATENT OFFICE.

WILBER F. SOUTHARD, OF BERLIN, ARKANSAS.

CHURN.

SPECIFICATION forming part of Letters Patent No. 282,232, dated July 31, 1883.

Application filed April 3, 1883. (No model.)

To all whom it may concern:

Be it known that I, WILBER F. SOUTHARD, a citizen of the United States, residing at Berlin, in the county of Johnson and State of Arkansas, have invented certain new and useful Improvements in Churns; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to churn-motors; and it consists in the novel construction and arrangement of its parts, hereinafter particularly described.

In the accompanying drawings, Figure 1 represents a perspective view of my motor with the churn-dasher attached. Fig. 2 represents a bottom plan view of the base A with its legs *a* *a* folded back under the same.

This base A is made of plank, and of sufficient width and length to give the upright B a steady foundation. This base has screwed across either end strips *a'* *a'*, to prevent it from warping or splitting. The strip *a'* is cut short to allow room for the articulation of the legs *a* *a*, which are pivoted on the under side of and to the rear end of this base, and are capable of being thrown out to the rear, as shown in Fig. 1. These legs are to steady the motor, the front feet of the chair in which the operator sits being placed in the holes *a'* *a'* thereof. When the motor is operated by a child, the child may stand on these legs to keep the motor steady. From the top side of this base I raise an upright, B. In the upper end of this upright I mortise two arms, C C, transversely, one end of each of which extends forward about eighteen inches, having sockets *c* *c*. These arms C C also extend to the rear of this upright about six or eight inches, and have secured between them, pivoted at its center by pin *b*, lever D, having hand-holds *d* *d*. This lever has rigidly and firmly attached thereto a bow or half-wheel, E, coming round in front of upright B and working between arms C C.

My dasher-handle F is made to fit into the sockets *c* *c* of the arms C C, and is kept from rising or falling by means of grooves *f* *f*, run-

ning around the dasher-handle, and forming a pulley, *i*, between the grooves. These sockets have straight sides, and are open on their outer end, so that the dasher-handle can be easily removed. When the motor is being operated, the pulley *i* is kept in the sockets by the cord K. On the lower end of the handle F, I secure a churn-dasher, G, intended to agitate the milk, and in the dasher-handle I make holes *h* *h*, for holding feathers or fans to chase away the flies and fan the operator in warm weather. I take a cord, K, and tie it around hand-holds *d* of lever D, bring it forward and around the pulley *i* once or twice between the grooves *f* *f*, then draw it along the face of the bow or half-wheel E to screw *e*', wind it around this screw once or twice, then draw it a time or two around and under cleat *e*, and the cord is secured without the necessity of tying it.

In operating this motor, I place my seat to the rear of the same, placing the front feet of the chair in the holes *a'* *a'* of the legs *a* *a*. I take hold of the hand-holds *d* *d* and work the ends of the lever D back and forth. This causes the dasher G to rotate with great speed, causing the butter to rise in an incredibly short time. When I wish to remove the churn and dasher, I unwind the cord from under cleat *e* and from around screw *e*', and the handle is at once loose and comes out of sockets *f* *f*, and is taken from the cord and churn and another churn placed in position and the dasher adjusted as before. Thus it will be seen that my dasher is put in place in a moment of time and removed as quickly, as I have no knots to tie or untie.

The cord hugging the face of the bow or half-wheel E, which is a perfect half-circle, pulls all the time on the handle in the same line, giving an even, regular, and consequently easy motion. This bow or half-wheel is of greater circumference than the circumference of the pulley *i*, in order to give the dasher great speed, while the operator is moving the lever with the ordinary movement usual and agreeable to human muscular action, as unusual muscular action soon fatigues the operator and heats the blood.

I am aware that a churn-motor has been heretofore constructed with a base having a somewhat similar upright and arm to mine, and a

dasher-shaft rotated by leather straps secured to the same and to a lever somewhat similar to mine, and these I do not broadly claim; but

What I do claim as new, and desire to secure 5 by Letters Patent, is—

The combination of base A, having perforated folding arms *a*, with upright B, secured on the upper face of said base and having arms C C transversely mortised into its upper end, 10 to the front ends having sockets or half-bearings *c c*, with lever D, pivoted at its center between the rear ends of arms C C, and bearing-bow or half-wheel E, working in front of upright B

and between the front ends of arms C C, dasher-shaft F, having pulley *i* and grooves *f* 15 *f*, said grooves working in sockets *c c*, and cord K, one end secured to handle *d*, then passing around pulley *i*, and secured to the other end of said lever by means of screw *e'* and cleat *e*, substantially as shown and described. 20

In testimony whereof I affix my signature in presence of two witnesses.

WILBER FERDINAND SOUTHDARD.
